(57) **CLAIM**

The ornamental design for a battery charging case for mobile devices, as shown and described.

DESCRIPTION

FIG. 1 is a Top Front Side Perspective view of the battery charging case for mobile devices.

FIG. 2 is a Top Rear Side Perspective view thereof.

FIG. 3 is a Front view thereof.

FIG. 4 is a Rear view thereof.

FIG. 5 is a Left view thereof.

FIG. 6 is a Right view thereof.

FIG. 7 is a Top view thereof.

FIG. 8 is a Bottom view thereof.

FIG. 9 is a Top Front Side Perspective view thereof.

FIG. 10 is a Top Rear Side Perspective view thereof.

FIG. 11 is a Front view thereof.

FIG. 12 is a Rear view thereof.

FIG. 13 is a Left view thereof.

FIG. 14 is a Right view thereof.

FIG. 15 is a Top view thereof; and,

FIG. 16 is a Bottom view thereof.

The broken lines shown in the drawings depict portions of the battery charging case for mobile devices which form no part of the claimed design.
